CIGARETTE DISPENSER

John B. Whitted, Glencoe, Ill.

Application August 28, 1937, Serial No. 161,381

13 Claims. (Cl. 312—77)

My invention pertains to cigarette dispensers and is particularly concerned with the provision of a cigarette dispenser for homes and offices.

An object of my invention is to provide an attractive cigarette dispenser composed of a few simple and inexpensive parts which may be quickly assembled and which will be durable and trouble-free in use.

Another object of my invention is to provide a cigarette dispenser which may have its larger parts composed of the new and more attractive plastics molded into attractive shapes and designs.

Another object of my invention is to provide a cigarette dispenser which may be made in either single or multiple form and which may, if desired, have an ash tray integral therewith.

Another object of my invention is to provide a cigarette dispenser which may be formed as a separate and attractive article or which may be attractively combined with fountain pen desk sets and similar articles commonly associated with desks and tables in offices and homes.

Another object of my invention is to provide a cigarette dispenser which will dispense either oval or cylindrical cigarettes of all makes.

Another object of my invention is to provide a cigarette dispenser which will dispense either tipped or untipped cigarettes.

Another object of my invention is to provide a dispenser which may be easily loaded with the contents of an ordinary package of cigarettes without the necessity of any pre-arrangement of the cigarettes as they are placed into the dispenser.

Another object of my invention is to provide a cigarette dispenser which will dispense a plurality of cigarettes simultaneously.

Other objects and advantages will become apparent as the description proceeds.

In the drawings:

Figure 1 is a perspective view of one embodiment of my invention;

Figure 2 is a longitudinal vertical section of the embodiment shown in Figure 1;

Figure 3 is a fragmentary view similar to Figure 2 but showing the parts in dispensing position;

Figure 4 is a horizontal section taken on the line 4—4 of Figure 2;

Figure 5 is a slightly irregular section taken substantially on the line 5—5 of Figure 2; and

Figure 6 is a side elevation showing a multiple form of my invention, a part of one side being broken away to show the interior construction.

Referring to Figures 1 to 5 inclusive, I have

shown my improved cigarette dispenser as having a housing 10 which may be made of metal, a phenol condensation product, or any other suitable material. I find it preferable, however, to form this housing 10 in a single part molded from 5 one of the newer plastics which can be secured in a wide variety of attractive colors and finishes. This housing as thus formed comprises a top 12, back 14, and sides 16 which extend forwardly at their lower portions to provide an integral ash 10 tray and cigarette holder 18. As shown most clearly in Figure 2, the rim of the ash tray 18 is made of V-shape and is provided with enlargements 20 forming rests for lighted cigarettes.

Within the housing 10 is located a cigarette 15 container 22 which may also be formed of metal or any other suitable material but which I preferably form as an integral member of plastic material such as a phenol condensation product. This container is adapted to hold the cigarettes in 20 vertical position as indicated most clearly in Figure 2 which shows this container in its normal position. The sides of the container 22 extend downwardly below the bottom 24 of the container as indicated most clearly at 26 in Figure 5, and 25 these downwardly extending sides are pivotally mounted on a rod 28 secured to the housing 10 in a manner which I shall presently describe. The container 22 has formed integrally therewith, a semi-cylindrical apron 30 which extends from 30 the main portion of the container 22 to a position adjacent the front edge 32 of the housing 10 which, in the particular embodiment disclosed in Figures 1 to 5, inclusive, forms the rear inner wall of the ash tray 18. Integral with the apron 30 35 is a handle 34 which may be engaged by a finger to swing the container 22 to the dispensing position shown in Figure 3.

The sides of the container 22 are provided with vertical slots 36 which slidably receive a U-shaped 40 wire 37 having a central portion 38 and upwardly directed ends 40. When the parts are in the normal position shown in Figure 2, the central portion 38 of this wire is located below the bottom 24 of the container 22 and the upwardly inclined 45 ends are spaced from the pivoted cover 42 which normally closes the upper end of the container 22. This U-shaped wire is held in this position by arms 44 which are formed by the reversely bent ends of a single piece of wire. Each arm 50 44 defines a slot which receives the central portion 38 of the U-shaped wire 37.

The arms 44 are pivotally mounted on a second rod 46 as, for example, by wrapping the wire, of which these arms are formed, about the rod 46 55

as clearly shown in the drawings. The central portion of the wire 48 of which the arms 44 are formed is engaged by one end 50 of a spiral spring 52 which is wound about the rod 46 and which has its other end 54 engaging the rod 28 as an abutment.

The end 50 of the spring 52 acts upwardly on the wire 48 and thereby urges the arms 44 downwardly whereby the U-shaped wire 37 is held in its downward position and with its central portion 38 engaging and pressing downwardly on the tail 56 of a lever 58 pivoted on the rod 28 and having an upwardly extending arm 60 passing through a slot 62 in the container 22. A pusher plate 64 is secured to the upper end of the arm 60 by means of a pin 66 which extends loosely through an opening in the upper end of the arm 60 and which also extends through suitable openings provided in flanges 68 struck out of the plate 64. This, in effect, provides a universal connection between the pusher plate and arm 60 so that the pusher plate may adjust itself to different groupings of the cigarettes in the container 22.

The cover 42 is provided with integral ears 70 having openings for receiving the ends of a mounting wire 72 which also passes through ears 74 integral with the back of the container 22. The wire 72 is preferably made U-shaped as shown in Figure 5 and carries on its central portion a sleeve 76 of rubber or other suitable material which acts as a bumper to cushion and limit the return movement of the container 22 into the housing 10.

The normal position of the container 22 is illustrated in Figure 2 of the drawings. The container is held in this position by a coil spring 78 having one end attached to the rod 46 and its other end attached to a wire 80 secured to a downward extension 82 formed integrally with the back of the container 22. The lower end of the housing 10 is closed by a plate 84 of metal or other suitable material which may be secured to the housing as by screws 86. The plate 84 is provided with longitudinal grooves 85 which stiffen this plate and which also permit the heads of the screws 86 to be flush with the lower face of the plate 84.

I preferably secure a layer of felt 88 or other soft material by an adhesive or other suitable means to the lower face of the plate 84 to prevent this plate from scratching the top of a desk, table or other piece of furniture.

When the parts are at rest, they assume the position shown in Figure 2 wherein the cigarettes are pushed against the front of the container 22 by the pusher plate 64. The upper end of the container 22 is closed by the cover 42 which prevents undue drying of the tobacco in the cigarettes. If desired, a moist sponge may be located in the space beneath the container 22 to maintain the cigarettes in the best possible condition.

When the handle 34 is pushed down to move the container 22 toward the position shown in Figure 3, the U-shaped wire 37 is moved upwardly, but the relationship of the parts is such that the central portion 38 of this wire does not rise above the bottom of the container until the upper front edge of the container is well beyond the top 12 of the housing 10. When the front upper edge of the container 22 has moved well beyond the top 12, the central portion 38 of this wire engages the lower ends of the cigarettes in the front or right hand row and pushes them up-

wardly until they assume the position shown in Figure 3.

As the central portion 38 of the U-shaped wire rises, it releases the tail 56 of the lever 58, whereupon the light spring 90 moves this lever in a counter-clockwise direction and shifts the pusher plate 64 to the inoperative position shown in Figure 3, thereby removing all pressure from the cigarettes and permitting the front row freely to slide upwardly under the urging of the wire 37. The spring 90 is coiled about the rod 28 and has one end 92 engaging the bottom of the container 22 and another end 94 engaging a lateral extension 96 of the tail portion 56 of the lever 58. As best shown in Figure 4, the lever 58 is made of sheet metal and the laterally extending portion 96 terminates in a reversely bent end 98 providing a second bearing on the rod 28.

As the rear top edge of the container 22 approaches the front edge of the top 12, the upwardly extending ends 40 of the wire 37 engage the cover 42 and raise it until it assumes the full opened position shown in Figure 3 of the drawings. When the container 22 is in the position shown in Figure 3, the rod 46 is located in recess 100 provided in the downwardly extending sides of the container and the limit of pivotal movement of the container is determined by the engagement of this rod 46 with the tops of these recesses. If desired, suitable bumpers may be provided either on the rod 46 or on the upper portions of these recesses to cushion the pivotal movement of the container 22. The container 22 is held in the dispensing position shown in Figure 3 by its own weight and also by the coil spring 78 whose direction of force has been moved to the other side of the pivot rod 28 by the movement of the container.

After the desired number of cigarettes has been withdrawn, a push on the front of the container 22 or on the handle 34 will return the container to the normal position shown in Figure 2. As the container swings back to vertical or normal position, the U-shaped wire 37 is lowered from beneath the front row of cigarettes and also from beneath the cover 42, so that the elevated cigarettes in the front row and the cover return to their lowered positions by gravity. It should be noted that during this return movement, the pusher plate 64 does not press upon the cigarettes and therefore does not retard the lowering of the elevated cigarettes. In the event one or more of the elevated cigarettes should fail to return under the force of gravity alone, the cover 42 will return such cigarettes to lowered position. Under certain circumstances, the engagement of the cover 42 with the top 12 will facilitate such return movement of the cigarettes. As soon as the central portion 38 of the U-shaped wire 37 engages the tail 56 of the lever 58, the pusher plate 64 engages the cigarettes in the container 22 and refills the front or right hand row. It should be noted that as the pusher plate 64 first moves away from the back of the container 22, it rises slightly, thereby tending to lift the cigarettes. This lifting action materially facilitates the proper feeding of the cigarettes to the front of the container 22.

An important feature of my invention lies in the ease with which it may be filled with the contents of an ordinary package of cigarettes and the accuracy and reliability with which these cigarettes are handled. In order to facilitate loading of the container and proper dispensing of the cigarettes placed therein, I pref-

erably make this container of such size that it will readily receive a full package of cigarettes of any standard make or shape but which will not permit any cigarette to rest at such an angle 5 crosswise of the container that it will not be raised above the edge of the container by the dispensing mechanism. I have found that where the interior of the container from front to back is made approximately 1½ inches and the interior 10 dimension of the container from side to side is made approximately 1¾ inches, perfect operation obtains. When the container is given these dimensions, it is sufficiently large to receive easily the contents of a full package of 15 cigarettes; no pre-arrangement of the cigarettes in the container is necessary; and every cigarette including the last one will be properly dispensed.

The particular arrangement of parts which 20 produces the upward movement of the wire 37 is particularly advantageous in that this wire is given a large movement for a comparatively small angular movement of the container 22; the upward movement of the wire 37 is first slow 25 to permit the upper end of the container to clear the top 12 and thereafter rapid to produce the necessary elevation of the cigarettes and top 42; and sufficient force is exerted on this wire 37 to insure dispensing of a full row of cigarettes 30 in spite of resistance offered by the inter-engagement of protuberances on the cigarettes due either to inaccuracy in manufacture or to the presence of cork or other tips. On the return movement of the container 22, there is likewise 35 adequate power available to lower all of the elevated cigarettes in spite of similar resistance.

The fact that my cigarette dispenser dispenses a plurality of cigarettes simultaneously, 40 is also especially advantageous. This means that a single operation of the dispenser will provide sufficient cigarettes for several people and even where only one person desires a cigarette, a better impression is created if he is given the 45 opportunity to select from a group of cigarettes instead of being confined to the single cigarette.

Another important feature of my invention lies in the simplicity of the parts and their ease 50 of assembly. The housing 10 and container 22 each comprises a single unitary molded structure and the bottom closure 84 is a simple plate which may be punched out of conventional material. Similarly, the pusher plate 64, lever 60 and cover 42 may be metal stampings made from 55 conventional material. The other parts are either easily bent out of conventional wire which is readily obtainable, or are already available on the commercial market as commercial springs now used for other purposes.

60 Particular attention is directed to the ease of assembly and disassembly. The rods 28 and 46 rest in grooves provided in the portions 102 of the molded housings 10, which grooves define the positions of the rods 28 and 46. The rods 65 are held in these grooves by metal plates 104, each of which is suitably secured to the housing 10 as by a single screw 106. This means for securing the operative parts of the structure in the housing 10 is particularly desirable from an 70 assembly standpoint.

It is to be understood that the combined cigarette dispenser and ash tray shown in Figures 1 to 5 is only one of the numerous forms which may be assumed by my invention. One of the 75 important advantages of my cigarette dispenser

lies in the fact that it may assume innumerable attractive and desirable shapes and designs and may be used either with or without an ash tray as desired. Similarly, it may be combined with desk fountain pen sets and other articles commonly used on desks and tables to provide a more attractive, convenient and useful piece of equipment for home or office. 5

My cigarette dispenser may also be made in either the single form shown in Figures 1 to 5 10 inclusive, or in the multiple form such as I have illustrated in Figure 6. In this Figure 6 I have embodied my invention in a form which is capable of dispensing two different kinds of cigarettes. Furthermore, in this form of my invention the dispenser may be so operated as to make both forms of cigarettes available simultaneously or either form alone, as desired. 15

The embodiment of Figure 6 comprises a single unitary housing 110 preferably molded from one 20 of the newer plastic materials. A pair of containers 22' are located in the housing 110. These containers 22' may be similar in all respects to the container 22 of the embodiment previously described, and each container 22' is provided 25 with a handle 34 for independent actuation. Simultaneous actuation of the containers 22' is effected by means of a handle 112 which may also be used for the purpose of transporting the cigarette dispenser from one location to another. 30

The handle which I have designated generally by reference character 112 comprises a loop 114 having a pair of slots 116. One end of an actuator 118 is located in each of the slots 116. These ends of the actuators 118 are provided with rigid 35 washers 120 located below the loop 114 and washers 122 located thereabove. The washers 120 and 122 are preferably rounded where they contact the loop 114 to permit pivotal movement 40 by this loop and each of the actuators. 40

The lower ends of the actuators 118 are bent in opposite directions as indicated at 124 and are received in suitable openings provided in the lower ends of the containers 22'. It is to be understood that the lower ends of the actuators 45 118 are offset on opposite sides of the center line of the cigarette dispenser so that they do not interfere with the levers which operate the pusher plates which are identical with the pusher plate shown in the first embodiment. Each container 22' may be provided with a slot opposite 50 the actuator 118 for the other container, in order to facilitate insertion of these actuators into the space between the containers. It is to be further understood that each container 22' is provided 55 with feeding and dispensing mechanism identical with that disclosed in the first embodiment.

When it is desired to move both containers 22' to dispensing position, the handle 112 is grasped and raised. This pulls upwardly on the back 60 portions of the containers 22' and swings them to dispensing position. After the desired cigarettes have been withdrawn, a downward force is exerted on the handle 112 which returns the containers 22' to their retracted or normal position. 65

If it is desired to move only one dispenser 22' to dispensing position, the handle 34 of that dispenser is engaged by the finger to swing the dispenser to dispensing position. As this dispenser swings outwardly, its associated actuator 118 is raised, thereby causing the loop 114 to assume a tilted position as it pivots about its points of contact with the upper ends of the actuators 118. 70 75

The slots 116 provide for any lateral movement of the actuators 118 relative to each other.

In the embodiment of Figure 6, the housing 110 is not provided with an ash tray similar to the tray 18 of the previous embodiment. It will be understood, however, that if desired, the housing 110 may be provided with one or more ash trays of this type formed integral with the housing.

10 While I have illustrated and described two forms of my invention, it is to be understood that my invention is not limited to the forms shown, but may assume innumerable other forms and that the scope of my invention is to be limited solely by the following claims.

I claim:

1. A cigarette dispenser of the class described, comprising a housing, a container pivotally mounted in said housing, said container adapted 20 to hold a plurality of cigarettes in substantially vertical position, means for urging said cigarettes against one wall of said container, means reciprocable in said container adjacent said wall to elevate cigarettes adjacent said wall, and means operated by tilting movement of said container for reciprocating said elevating means.

2. In a cigarette dispenser of the class described, the combination of a container for holding a plurality of cigarettes, a support for said container, a pivotal connection between said support and container, a pivoted cover for said container, a bent rod movable relative to said container, said rod having a portion adapted to underlie a cigarette located in said container, and another portion adapted to underlie said cover, and means operated by movement of said container about its pivot to elevate said rod and thereby elevate a cigarette and lift said cover.

3. A cigarette dispenser of the class described, 40 comprising a housing, a cigarette container movably mounted in said housing and shiftable between extreme positions, said container adapted to hold a package of cigarettes, means for urging said cigarettes toward one wall of said container, 45 means for moving the cigarettes adjacent said wall relative to said container, means actuated by movement of said container to render said first-named means inoperative and to operate said second-named means, and means for holding 50 said container in either of its extreme positions.

4. In a dispenser of the class described, the combination of a support, a container pivoted on said support, said container having a slot therein, means for projecting an article located in 55 said container, said means comprising a member movable in said slot, a slotted lever engaging said member, and a pivotal mounting for said lever on said support, said last-named mounting being spaced at one side of said first-named pivotal 60 mounting.

5. In a dispenser of the class described, the combination of a container for holding a plurality of articles, means for feeding said articles toward a given part of said container, means for 65 projecting said articles, a support on which said container is movably mounted, means for advancing said feeding means, means operated by movement of said container in one direction to render said last-named means ineffective, and means 70 operated by movement of said container in said direction to actuate said projecting means.

6. In a dispenser of the class described, the combination of a container for holding a plurality of articles, a support for said container, a pivotal 75 mounting for said container, feeding means for

urging said articles toward one wall of said container, means for projecting said articles, means for operating said feeding means, means actuated by pivotal movement of said container for rendering said last-named means ineffective during operation of said projecting means, and means actuated by movement of said container for actuating said projecting means.

7. In a dispenser of the class described, the combination of a container, a movable cover therefor, a support movably carrying said container, said container being adapted to hold a plurality of articles, means for feeding said articles toward a pre-determined part of said container, means for projecting said articles, and means responsive to movement of said container for raising said cover and actuating said projecting means and rendering said feeding means ineffective.

8. In a cigarette dispenser of the class described, 20 the combination of a container of suitable size for easily receiving, without pre-arrangement, the contents of a standard cigarette package, a support movably holding said container, a cover pivoted to said container, and means actuated by 25 movement of said container to open said cover and project a plurality of said cigarettes, said means being independent of said cigarettes.

9. In a cigarette dispenser of the class described, 30 the combination of a housing, a container pivotally mounted therein, a cover movably attached to said container, means for projecting cigarettes from said container, means for raising said cover, means for coordinating the operation of said raising and projecting means with pivotal movement 35 of said container, and a portion provided by said housing for returning said cover to closed position and returning any projecting cigarettes to said container.

10. In a dispenser of the class described, 40 the combination of a support, a container, a rod pivotally mounting said container on said support, means for projecting articles from said container, said means associated with said container, said projecting means including a lever, 45 a second rod forming a pivotal mounting for said lever, said support having abutments for said rods, and a plate removably attached to each abutment for securing said rods to said support.

11. In a cigarette dispenser of the class described, 50 the combination of a holder, a plurality of containers movably mounted therein, article-projecting means associated with each container, and a handle for creating simultaneous movement of said containers, said handle being pivotally connected to each container to permit independent movement thereof.

12. In a cigarette dispenser of the class described, the combination of a support, a cigarette container pivoted thereon, article-projecting 60 means actuated by pivotal movement of said container, feeding means associated with said container for urging cigarettes toward one wall of said container, said feeding means including a lever having an end located in said container, a 65 pusher plate universally connected to said end, a pivotal mounting on said support for said lever positioned to give said plate an initial upward and forward movement relative to said container, and spring means normally acting on said lever 70 to advance said plate.

13. In a cigarette dispenser of the class described, the combination of a support, a container for cigarettes pivoted on said support, means for feeding said cigarettes toward a given part of said 75

5 container, a cover movably attached to said container, means to raise said cover, means for simultaneously projecting a plurality of cigarettes after said cover has been raised, said feeding, projecting, and raising means being controlled in time sequence by movement of said container about its pivotal support, said cover being adapted

to facilitate return of projected but unused cigarettes to normal position in said container in response to another movement of said container, and a part provided by said support for assisting the cover in accomplishing this function. 5

JOHN B. WHITTED.
